UNITED STATES PATENT OFFICE.

ALBERT BOEHRINGER, OF MERIDEN, CONNECTICUT, ASSIGNOR TO EDWARD MILLER & CO., OF MERIDEN, CONNECTICUT, A CORPORATION OF CONNECTICUT.

DESIGN FOR A PEDESTAL.

53,284.

Specification for Design.

Patented May 13, 1919.

Application filed March 6, 1919. Serial No. 281,100. Term of patent 3½ years.

To all whom it may concern:

Be it known that I, ALBERT BOEHRINGER, a citizen of the United States, residing at Meriden, county of New Haven, and State of Connecticut, have invented a new, original, and ornamental Design for a Pedestal, of which the following is a specification, reference being had to the accompanying drawing, forming a part thereof.

In said drawing:

The figure is a perspective view of an ornamental pedestal embodying the design of my invention.

I claim—

The ornamental design for a pedestal substantially as shown.

ALBERT BOEHRINGER.
